UNITED STATES PATENT OFFICE.

EDWARD ALLEN GARDINER, OF WHIGLANE, NEW JERSEY.

VEHICLE-GEAR.

SPECIFICATION forming part of Letters Patent No. 375,148, dated December 20, 1887.

Application filed February 14, 1887. Serial No. 227,550. (No model.)

To all whom it may concern:

Be it known that I, EDWARD ALLEN GARDINER, of Whiglane, in the county of Salem and State of New Jersey, have invented a new and Improved Vehicle, of which the following is a full, clear, and exact description.

The object of my invention is to provide a new and improved vehicle which is simple and durable in construction.

10 The invention consists in the construction and arrangement of various parts and details and combinations of the same, as will be fully described hereinafter, and then pointed out in the claims.

15 Reference is to be had to the accompanying drawings, forming a part of this specification, in which similar letters of reference indicate corresponding parts in all the figures.

Figure 1 is a plan view of my improvement 20 with the wheels removed. Fig. 2 is an end elevation of the front part of the same. Fig. 3 is a similar view of the rear part of the same, and Fig. 4 is a section on the line $x-x$ of Fig. 2.

On the under side of the straight front axle, 25 A, is held the downwardly-extending truss B by means of the hangers C, supported by the axle A. The outer ends of the truss B are connected with each other by the strengthening-rod E.

30 In the middle of the truss B, next to the axle A, is formed a recess, F, for the passage of the rod G, connecting the front part of the axle with the rear part and held on the axle by the usual king-bolt. On top of the axle A is held the bolster H, provided on each end with the usual standard, I.

The hounds J are held under the truss B, and are strengthened by the brace K, running over the axle lengthwise with the hounds J, 40 and by the side braces, L, extending from the outer ends of the truss B to the ends of the hounds J, which are connected at their ends by the straight slide-bar N, resting under the connecting-rod G. The rear axle, O, is also 45 straight and supports a truss, P, on its under side by means of the hanger Q, secured to the axle O. The outer ends of the truss P are connected by the strengthening-rod R. In the truss P is also formed a recess for the passage of the connecting-bar G. The standards 50

S are secured directly to the top of the axle O, while to the under side of the axle is secured, near each end, a crotch, T, extending to the connecting-rod G. From each outer end of the truss F extends a crotch-brace, U, which unites 55 with the crotch T.

The several parts of my vehicle are made of wrought-iron and cast-steel, principally of steel, and as the various parts are arranged below the axle I am enabled to place the wagon-bed from six to eight inches lower than in the former style of wagon with as large wheel, thus permitting an easier loading or unloading of the wagon, and at the same time giving a natural or center draft and having less positive 65 tongue movement on rough roads; also, the steady carrying of loads on the same; also, using a lighter wheel with more service with fewer, separate, and distinct parts, with greater strength and less weight, with less draft, 70 unique, simple, practical, and durable.

Having thus described my invention, what I claim as new, and desire to secure by Letters Patent, is—

1. The combination, with the axle provided 75 with downwardly-projecting hangers, of a truss held to the axle by the said hangers, and a tie-rod extending under the said truss and having its ends connected to the ends of the truss, substantially as herein shown and de- 80 scribed.

2. The combination, with the axle A, provided with the hangers C, of the truss B, the tie-rod E, connecting the ends of the truss together, the hounds J, passing between truss 85 and tie-rod E, and the braces K, passing over the axle and having their ends connected to the hounds on opposite sides of the axle, substantially as herein shown and described.

3. The combination, with the front axle, A, 90 of the truss B, secured to the under side of the axle, the bar E, connecting the ends of the truss, the hounds J, secured to the under side of the truss, the bar N, connecting the rear ends of the hounds, and the braces K L, sub- 95 stantially as herein shown and described.

EDWARD ALLEN GARDINER.
